CARRYING TRAY FOR TUMBLERS OR THE LIKE

Melvyn S. Rifkind, 3452 Cochran Ave., Los Angeles,
Calif., and Roy F. Heatly, 21828 Chase St., Canoga
Park, Calif.

Filed Oct. 2, 1962, Ser. No. 71,956

Term of patent 14 years

(Cl. D44—10)

FIG. 2.

FIG. 3.

FIG. 4.

FIGURE 1 is a top perspective view of a carrying tray for tumblers or the like showing our new design.

FIGURE 2 is a top plan view thereof.

FIGURE 3 is a side elevational view thereof.

FIGURE 4 is an end elevational view thereof.

We claim:

The ornamental design for a carrying tray for tumblers or the like, substantially as shown.
